UNITED STATES PATENT OFFICE

FREDERICK L. G. STRAUBEL, OF GREEN BAY, WISCONSIN, ASSIGNOR TO THE AUTOMATIC FILE & INDEX COMPANY, OF GREEN BAY, WISCONSIN, A CORPORATION OF WISCONSIN

FILING CARD SUPPORT

Application filed March 3, 1930. Serial No. 432,751.

The invention relates to supports for filing cards and more particularly it relates to supports providing means for mounting a plurality of cards in overlapping relation with a relatively narrow strip of each card projecting from underneath an overlapping card to provide exposed indexing space.

Visible card supports of the kind described are well known to those familiar with the art, and it is an object of the invention to provide such a card support having novel means for protecting and reinforcing the lugs with which such cards are attached to and slidably mounted upon the support.

15. The invention contemplates a panel comprising two sheets of material suitably fastened together in juxtaposed relation, one of such sheets being indented to form one or more parallel elongated channels or depressions and the other of said sheets having slots in registry with said depressions or channels, one bounding edge of each of said slots projecting over a corresponding side of the depression, thereby forming shelves providing runways for the cards, with the lugs with which such cards are equipped projecting underneath the shelves. The lugs are thereby protected or braced by the shelves on one side and the bottom wall of the channel or depression on the other side. While the panel is shown as constructed of juxtaposed sheets suitably fastened together, it can, if desired, be constructed from a single sheet or panel similarly indented or equipped with shelves.

35. Another object of the invention is the provision of a card support of the kind described which is durable, compact, simple and satisfactory for its intended purpose.

40. Many other objects and advantages of the construction herein described and shown will be obvious to those skilled in the art from the disclosure herein given.

To this end my invention consists in the novel construction, arrangement and combination of parts herein described and shown and more particularly pointed out in the claims.

45. In the drawings, wherein like reference characters indicate like or corresponding parts,

Fig. 1 is a perspective view of a panel embodying the devices of my invention;

Fig. 2 is a section along the line 2—2 of Fig. 1; and

55. Figs. 3, 4, 5 and 6 are sectional views along the lines 3—3, 4—4, 5—5, and 6—6, respectively, of Fig. 1.

Referring now more particularly to the drawings, the numeral 10 generally designates a panel providing a mounting for a 60 plurality of filing cards. The panel 10 may be positioned vertically in a standard filing drawer, or it may, if desired, be hinged at one end and rotated or swung about a vertical axis.

65. The panel 10 comprises a front sheet 11 and a back sheet 12, both of which are preferably constructed from light, strong metal, such as aluminum. The sheets 11 and 12 are fastened together in close relation by a plurality of countersunk rivets or pins 9. The 70 dimensions of the front sheet 11 are greater than the dimensions of the back sheet 12. The projecting ends and edges of the sheet 11 are folded to form suitable flanges. The upper edge of the sheet 11 is folded rearwardly over the top edge of the back sheet 12, the folded portion forming a reinforcing strip 14. The lower portion of the sheet 11 is curved rearwardly under the bottom edge 75 of the sheet 12 and then forwardly to form a tubular-shaped bottom edge 16 for the panel 10. The extreme edge of the sheet 11 is folded upwardly to form a front reinforcing strip and spacer member 13 preventing 80 the cards mounted thereabove from coming into contact with the next adjacent panel or spacer guide. This arrangement prevents unnecessary wear and tear upon the exposed 85 faces of the cards. The tubular-shaped bottom edge 16 of the panel 10 enables the panel to be easily tipped forwardly and backwardly in the drawer in which it is positioned without tending to mar or scar the drawer.

90. The extra length of material in the sheet 11 is utilized by folding it around the end edges of the back sheet 12 to form side reinforcing strips 15. The strips 14 and 15 aid the rivets 9 in holding the sheets 11 and 12 95 100.

with their adjacent faces in close contact and prevent any relative movement of the sheets. The sheet 12 is notched in its upper left-hand corner and an aperture 17 in the upper left-hand corner of the sheet 11 overlying the notch in sheet 12 provides a window for indexing the panel.

The back sheet 12 is provided with two pairs of vertically extending parallel projections 18 in its rear face forming corresponding depressions or channels 19 in the front face of the sheet. A plurality of slots 20 formed in the front sheet 11 extend the full length of and register with the channels 19.

15 The slots 20 are arranged in pairs or groups of two each, separated by a relatively narrow strip of material 23 which projects at each edge over the adjacent channel or depression 19, and forms shelves 21. The shelves 21 are offset slightly outwardly to provide runway spaces 22 between the shelves and the bottom of the channel 19. The panel 10 is shown as having two pairs 25 of such runways 22 but it is obvious that one or any number more than one may be provided in a panel. Each pair of spaces 22 is adapted for mounting a row of cards 26 therein by the insertion of lugs 25 die-stamped or otherwise cut in the cards 26, 30 one of which is shown in dotted lines in Fig. 1.

The cards 26 are mounted on the panel 10 by bending or tucking the lugs 25 into the runway spaces 22. The first card thus inserted may be pushed downwardly back of the strip 13 and other cards in turn are inserted and arranged in overlapping relation. The lugs 25 being easily bent or broken are 40 the vulnerable portion of the filing cards 26. In card supports as heretofore constructed, the lugs have been positioned in an open slot, leaving them exposed to wear and tear and breakage. By the improved device constituting my invention, the lugs are 45 protected and braced or reinforced on both sides in the spaces 22 and the wear and tear thereon is reduced to a minimum. A plurality of cards 26 can thus be mounted in one pair 50 of runways or spaces 22, each card, other than the lower one, being positioned back of the next card below except for an exposed strip the width of which is determined by the distance of the bases of lugs 25 from 55 the lower edge of the card. The exposed upper edge strip provides sufficient space for the indexing material.

Thus it will be seen that the invention provides a filing card support having enclosed runways or spaces in which the projecting lugs of the filing cards are positioned, the walls of said spaces serving to protect and reinforce the lugs and minimize the wear and tear thereon.

65 Having thus described my invention, it

is obvious that various immaterial modifications may be made in the same without departing from the spirit of my invention; hence I do not wish to be understood as limiting myself to the exact form, construction, arrangement and combination of parts herein described and shown, or uses mentioned. What I claim as new and desire to secure by Letters Patent is:

1. A card support of the kind described 75 comprising a panel having a pair of parallel elongated channels in one face and corresponding projections on the other face, one edge of each of said channels having a shelf projecting thereover.

2. A card support of the kind described comprising a panel having a pair of parallel elongated channels in one face and corresponding projections on the other face, the adjacent edges of said channels each having 85 a shelf projecting thereover.

3. A card support of the kind described comprising a panel having a pair of parallel elongated channels in one face and corresponding projections on the other face, the adjacent edges of said channels each having 90 a raised shelf projecting thereover.

4. A card support of the kind described comprising a panel made up of two sheets 95 of material arranged with their adjacent faces in juxtaposed relation, one of said sheets having an elongated channel formed therein and the other of said sheets having a slot in registry with said channel, one bounding edge of said slot forming a shelf projecting over said channel.

5. A card support of the kind described comprising a panel made up of two sheets of material arranged with their adjacent faces in juxtaposed relation, one of said 105 sheets having an elongated channel formed therein and the other of said sheets having a slot in registry with said depression, said slot being narrower than the channel with which it registers, one bounding edge of said slot forming a shelf projecting over said channel.

6. A card support of the kind described comprising a panel made up of two sheets 115 of material arranged with their adjacent faces in juxtaposed relation, one of said sheets having a plurality of parallel elongated channels formed therein, the other of said sheets having slots formed therein in registry with said channels, one bounding edge of each slot forming a shelf projecting 120 over its corresponding channel.

7. A card support of the kind described comprising a panel made up of two sheets of material arranged with their adjacent 125 faces in juxtaposed relation, one of said sheets having a pair of parallel elongated channels formed therein, the other of said sheets having slots registering with said channels, the inner bounding edges of said 130

slots forming shelves oppositely projecting over said channels.

8. A card support of the kind described comprising a panel made up of two sheets of material arranged with their adjacent faces in juxtaposed relation, one of said sheets having a plurality of parallel elongated channels formed therein, the other of said sheets having slots formed therein in registry with said channels, one bounding edge of said slots being offset outwardly and projecting over the corresponding channels.

9. A card support of the kind described comprising a panel made up of two sheets of material arranged with their adjacent faces in juxtaposed relation, one of said sheets having a plurality of parallel elongated channels formed therein in pairs, the other of said sheets having slots formed therein in registry with said channels, one bounding edge of said slots being offset outwardly and projecting over the adjacent edges of corresponding channels.

In witness whereof, I hereunto subscribe
25 my name this first day of February, A. D.
1930.

FREDERICK L. G. STRAUBEL.
